MAGNIFYING ATTACHMENT FOR LOOPING MACHINES

Joseph Haines, Jr., Meadowbrook, Pa., assignor to
Haines Hosiery Mills, Inc., Philadelphia, Pa., a
corporation of Pennsylvania

Original application February 19, 1932, Serial No.
594,028. Divided and this application March 17,
1933, Serial No. 661,208

8 Claims. (Cl. 88—39)

This invention is a division of a pending application Serial No. 594,028 filed by me on February 19, 1932, and relates to magnifying attachments intended more particularly for circular or dial 5 looping machines such as are used in hosiery mills to close the toe ends of stockings.

In operating machines of the kind referred to, the loops along the terminal edges at opposite sides of the stocking toes are superposed and impaled by hand upon the radially-projecting points of the looper dial as said points move past the operative, the superposed loops being afterwards united as they advance through the sewing mechanism of the machine. This "running on" operation is not only very exacting, but tedious by reason of the fineness and closeness of the fabric loops.

The aim of my invention is to facilitate the work of the operators of looping machines, and at the same time relieve eye strain, through provision of a magnifying attachment which is simple and inexpensive in construction; which is easily applied to the machines; which permits universal adjustment of the glass in the line of vision for clear magnification of the dial points as they pass so that the fabric loops can be run onto the points with the utmost ease and quickness without attendant danger of loop dropping; and which is moreover shiftable to and fro about the axis of the machine to permit allocation of the glass over the points at any position of the dial.

In the drawing, Fig. I is a fragmentary plan view of a circular looping machine fitted with my improved magnifying glass attachment.

Fig. II is a fragmentary side elevation of the organization; and,

Fig. III is a detail view showing how the magnifying glass is secured to the supporting arm provided for it on the looping machine.

With more detailed reference to this drawing, the numeral 5 designates the dial of the looping machine; 6, the fixed vertical stud about which the dial rotates; and 7, the supporting bracket for the stud.

In the illustrated embodiment, my improved magnifying glass attachment comprises a split collar 8 with bolts 9, 10 whereby it is frictionally clamped to the upper end of the stud 6; and a longitudinally extensible arm 11 which is fulcrumed on the bolt 9 of the collar 8 so that it, together with the parts supported thereby, may be swung upward out of the way from the normal illustrated position horizontally over the dial 5. As shown, the arm 11 consists of two relatively adjustable bar sections 11a, 11b, both of which are

longitudinally slotted, and which are securable after adjustment by a pair of screw bolts 12 with winged clamp nuts 13. At its outer end, the arm 11 carries a vertical bracket member 14 which is longitudinally slotted for adjustment vertically and along said arm, the adjustment being fixed by a screw bolt 15 and wing nut 16. In turn secured to the bracket member 14 by means of a screw bolt 17 and wing nut 18 with capacity for up and down and angular adjustment, is the magnifying glass 19. Also associated with the arm 11 is another longitudinally slotted vertical bracket member 20, which, at its lower end, has a roller 21 to run on the top surface of the dial 5 of the looping machine. A screw bolt 22 and wing nut 23 serve to adjustably secure the bracket member 20 to the arm 11.

The several described adjustments obviously permit very accurate focal positioning of the magnifying glass 19 in the line of the operator's vision over the radially-projecting points 24 of the dial 5. Thus, with the arm 11 positioned as shown in Fig. I and held against rotating with the dial 5 by the frictional restraint of the collar 8, the dial points 24 are magnified as they pass in front of the operator thereby greatly facilitating impalement upon them of the fabric loops. Furthermore, the operator may, if necessary, swing the arm 11 in one direction or the other horizontally about the axis of the looping machine by virtue of the yielding frictional connection of the clamp collar 8 with the stud 6, to bring the magnifying glass 19 over the points 24 at different portions of the dial 5 for detection of any dropped loops before the stockings enter the sewing mechanism of the machine. Also, as hereinbefore stated, the arm 11 and its appendages may, when required, be swung up out of the way about the fulcrum 9.

From the foregoing it will be apparent that I have provided a simple and inexpensive magnifying attachment which will greatly relieve eye strain and thereby render the operation of looping easier with corresponding gain in the output of the looping machines.

Having thus described my invention, I claim:

1. A magnifying glass attachment for looping machines, including a dial, comprising an extensible arm horizontally overreaching and in part sustained by the looper dial, and means supporting the magnifying glass from said arm with provision for universal adjustment in the line of the operator's vision over the dial points.
2. A magnifying glass attachment for looping machines, including a rotary dial, comprising a

- supporting arm overreaching the rotary dial, said arm being fulcrumed at its rear end so that it may be swung up and down and being normally sustained horizontally by a roller running on the top of the rotary dial; and means securing a magnifying glass to the outer end of the arm with provision for universal adjustment in the line of the operator's vision over the dial points. 80
- 5 3. A magnifying glass attachment for looping machines, including a rotary dial, comprising a longitudinally-extensible horizontal arm overreaching the rotary dial, said arm being fulcrumed at its rear end so as to be swingable up and down and being normally sustained horizontally by a roller running on the top of the rotary dial; and means securing a magnifying glass to the outer end of the arm with capacity for universal adjustment in the line of the operator's vision over the dial points. 85
- 10 4. A magnifying glass attachment for looping machines, including a rotary dial, comprising a supporting arm horizontally overreaching the rotary dial, said arm being fulcrumed so that it may be swung up out of the way when required; a bracket member vertically adjustable relative to the arm and carrying a roller at its lower end to run in contact with the top of the rotary dial; and means securing a magnifying glass to the outer end of the arm with capacity for universal adjustment in the line of the operator's vision over the dial points. 90
- 15 5. A magnifying glass attachment for looping machines, including a rotary dial, comprising an arm overreaching and in part sustained by the rotary dial; a bracket member secured to the outer end of the arm, said bracket member being adjustable lengthwise as well as vertically of the 95
